Primary Examiner — Caron D Veynar*Assistant Examiner* — Melvin Davis(74) *Attorney, Agent, or Firm* — Shook, Hardy & Bacon L.L.P.(57) **CLAIM**

The ornamental design for a jacket, as shown and described.

DESCRIPTION

FIG. 1 is a right front perspective view of a jacket according to the present design;

FIG. 2 is a front view thereof;

FIG. 3 is a right side view thereof;

FIG. 4 is a left side view thereof;

FIG. 5 is a back view thereof; and,

FIG. 6 is an enlarged front view of FIG. 2, enlarged for clarity of details.

The evenly spaced broken lines represent parts of the article that form no part of the claimed design. The long and short lines represent the boundaries of the claim and form no part thereof. The inside of the hood forms no part of the claimed design.
